UNITED STATES PATENT OFFICE

2,567,263

SOFA BED

William W. Wilson, Memphis, Tenn.

Application May 26, 1945, Serial No. 595,894

9 Claims. (Cl. 5—47)

1

This invention relates to sofa bed hinges and supports of that well known type in which brackets pivotally hinged together are secured respectively to the lower end of the back and the rear end of the seat and the hinge is carried by a pair of upwardly extending swinging arms which are pivotally supported by attachment at their lower ends to a base member, and it further relates to the latch member and trip by which the seat and back are braced apart in certain positions and in others are interlocked to accomplish shift from sofa to bed positions and back again.

The objects of the present invention are:

To provide means for assisting in shifting the seat and back from sofa position;

To provide means for stopping the movement of the seat and back toward sofa position, as the seat and back reach such position;

To provide latch means which will positively remain in bracing position against any except intentional dislodgement;

To provide a latch and trip in which engagement of the trip with an abutment pin in movements of the seat from bed positions, is positive and accidental dislodgement is substantially impossible;

To provide a latch and trip in which disengagement of the abutment pin from the latch and trip in movement from an intermediate shift position to bed position is definite and hanging is impossible; and

To provide a latch arm and trip of improved design and construction.

The means by which the foregoing and other objects are accomplished, and the manner of their accomplishment, will be readily understood from the following specification upon reference to the accompanying drawings, in which:

Fig. 1 is an end elevation of the sofa bed in sofa position.

Fig. 2 is an enlarged elevation of the latch and trip with the pivot and abutment pin in the positions which they occupy in Fig. 1.

Fig. 3 is a fragmentary elevation of a portion of one of the support arms, showing attachment of a spring thereto.

Fig. 4 is an end elevation of the sofa bed with the back shifted into bed position and the seat in furthest position of intermediate movement and ready to begin return movement to bed position.

Fig. 5 is an enlarged view of the latch and trip with the pivot and abutment pins in the positions which they occupy when the seat has been moved from sofa position to the position shown in Fig. 4.

2

Fig. 6 is a similarly enlarged fragmentary view of the latch dog and abutment pin when the seat has been shifted from bed position to the position shown in Fig. 4.

Fig. 7 is a similarly enlarged view of the latch and trip and abutment pin in the positions they occupy when the seat is in the dotted position of Fig. 4, returning the latch from the position shown in Fig. 6.

Fig. 8 is an end elevation of the sofa bed in bed position.

Fig. 9 is an enlarged view of the latch and trip and the pivot and abutment pins in the positions they occupy at such time.

Fig. 10 is a similar scale outline of the latch only; and

Fig. 11 a latch trip and abutment pin view in an intermediate position between the positions of Figs. 2 and 6.

Referring now to the drawings in which the various parts are indicated by numerals:

11 is the back of a sofa bed, and 13 the seat, 15 is a hinge member secured to the bottom edge of the back, and 17 the complementary hinge member secured to the rear edge of the seat, it being understood that these parts and substantially all the parts hereinafter described, are duplicated at the opposite end of the bed. 19 is a frame from which the seat and back are supported.

The hinge members 15 and 17 are pivotally connected by a pintle pin 21 and the hinge thus formed is supported by back and front arms 23 and 25, the back arm 23 being pivotally connected at its upper end to the hinge member 15 by a pivot pin 27 and at its lower end by a pivot pin 29 to the frame 19. The front arm 25 is pivotally connected at its upper end to the hinge by the pintle pin 21, and at its lower end to the frame 19 by a pivot pin 31.

The hinge member 17 extends rearwardly past the pintle pin 21 and carries a stop pin 33 which is adapted to engage and seat against a shoulder 23A on the arm 23 substantially at the junction of the shoulder with the front edge of the arm itself when the seat and back are shifted to sofa position. The back arm 23 has a rearwardly extending lug 23B to which a tension spring 36 is pivotally secured.

Secured to the front arm 25 as by a pivot pin 37, is a stop arm 39 which is of length to extend rearward beyond the back arm 23 in any and all positions, the stop arm 39 being provided with a slot 39A which embraces a pin 41 projecting from the arm 23. The pin 41 is positioned much

closer to the pivot 29 of the arm 23 than the pin 37 to the pivot 31 of the arm 25, providing a more rapid rearward movement of the slot 39A than of the pin 41, and causing the front end of the slot to seat against the pin 41 as the seat and back reach sofa position shown in Fig. 1.

The spring 35 is secured at its outer end, as by a pin 43, to the rear end of the arm 39, the arm being made of such length that when the seat and back are in sofa position the spring 35 will be under tension and acts to urge movement of the seat and back away from such sofa position. The spring 35 is secured to the inner sides of the lug 23B and of the stop arm 39 so that it overlies the upper edge of the adjacent member of the frame 19 and is shielded in all positions by the stop arm 39 and under and overlying portions of the frame and back from engagement with overhanging draperies of upholstery.

Cooperating with the hinge members 15 and 17 is a latch 45 which is pivotally attached at its rear end to the back hinge member 15 by a latch pivot pin 47 and at its front end is notched for engagement with an abutment pin 49 carried by the hinge member 17. The latch carries a dog 51 and is on the inner side of the hinge members, and, being substantially hidden in Figs. 1, 4 and 7, has been enlarged and shown in Figs. 2, 5, 6 and 8 respectively in the same position which it occupies in Figs. 1, 4 and 7, and as though the hinge members and arms had been cut away.

Adjacent its front end the latch 45 (Fig. 9) is upwardly notched and rearwardly recessed to form a rearwardly facing shoulder 45A at right angles to its bottom edge, and an opposite deeply recessed abutment pin seat 45B facing forwardly and downwardly toward said shoulder.

Rearwardly of the seat 45B the latch carries a pin 53 which forms the dog pivot. The rear side of the notch extends rearwardly downward and arcuately below the pin and the lower side 45C of the latch, and thence upwardly to a junction with the side 45C rearwardly of the pin, to form a camming shoulder 45D and divert the abutment pin 49 (Fig. 9) outward as it enters the dog throat 51F.

Adjacent the rear end of the latch is a hole 45E for the latch pivot pin 47. 55 and 57 are stops carried by the latch respectively forward and rearward of pin 53, which limit turning movement of the dog 51 in opposite directions. The dog 51 has a hole therethrough for the pivot 53 by which it is secured to the latch and on which it pivots. The dog is heavy on one side and much lighter on the opposite side, preferably about one-half 51A of the dog being semi-circular about the pin 53 to form the heavy half. 51B is a lug, preferably located at one end of the two halves, the opposite end of the heavy half is notched to form a recess extending away from the pivot pin 53, the recess having oppositely faced seats 51C and 51D respectively substantially the same distance from the pin 53 as are the latch seat 45B and the shoulder 45A from the same pin, and the throat 51F which leads into the inner end of the recess and the seat 51D, which is deeply indented. The other half of the dog is substantially narrower than the just described heavy half and the end opposite the lug 51B is truncated to form a cam 51G extending from the cam entrance throat 51F and terminating in a trip seat 51H, the cam being spaced from the pin 53 in excess of the depth of the camming shoulder 45D of the latch below the pin.

In use, when the seat and back are in sofa

70

position, as shown in Fig. 1, the front of the seat is supported by the frame 19 and the rear end of the seat and the back are supported by the arms 23 and 25, the back being braced against rearward movement by the pin 33 of the bracket 17, engaging the shoulder 23A substantially at the junction of the shoulder with the front edge of the arm 23, and additionally by seating of the forward end of the slot 39A against the pin 41, and the back is braced against forward movement by engagement of the notch of the latch 45, with the abutment pin 49, Fig. 2, the pin being at such time in the notch of the dog 51 and positioning the dog.

At the same time the spring 35 has been extended by rearward movement of the stop arm 39 and is exerting a forward pull on this arm and through it on the arm 25, tending to move the seat and back away from sofa position, but insufficient to actually cause such movement.

To shift from sofa position to bed position, the front edge of the seat is raised, the force necessary being decreased by the pull of the spring 35 on the arm 39. Initially the seat acts as a lever to raise the pin 21 about the pin 33 which is seated against the shoulder 23A as an abutment, and start the movement. As this upward movement of the seat begins the pin 49 is moved away from the latch seat 45B and from the contiguous seat 51C of the dog notch into engagement with the oppositely facing seat 51D of the notch, and also into engagement with the shoulder 45A at the front end of the latch, and through these engagements with the latch, pulls the back and the upper ends of the support arms 23 and 25 forward and upward about the lower support pins 29 and 31 of these arms, the movement of the upper ends of the arms concurrently swinging the upper end of the back rearward and downward.

As this movement progresses the center of gravity of the back is rearwardly shifted until, as the seat approaches the dotted position 13X, of Fig. 4 (and the latch, the position detailed in Fig. 7), the downward pull of the back becomes sufficient to accomplish further movements, and to change the pull of the latch 45 on the back to a push of the back on the latch, shifting the latch 45 forward and upward, disengaging the abutment pin 49 from the dog recess and seat 51D with the latch seat 45B (Fig. 7) and permits the over-balancing weight of the heavy half 51A of the dog to swing the dog into the position there shown, and stopped by engagement of the opposite seat 51C with the pin. As the seat reaches the dotted position 13X, of Fig. 4, the back seats on the frame 19 and further movement of the seat is pivotal about the pintle pin 21. Movement of the seat is, however, continued, shifting the abutment pin 49 outward and through the dog throat 51F until movement is stopped by the latch shoulder 45A, the seat being then in the position 13Y.

As the abutment pin 49 clears the dog throat 51F, the dog further turns under the action of gravity, until such turning movement is stopped by engagement of the lug 51B with the stop 55, this turning shift moving the cam 51G of the dog beneath the abutment pin. The seat is then returned from the position 13Y, of Fig. 4, to bed position, Fig. 8, the abutment pin camming along the surface 51G of the dog until the trip seat 51H is reached, after which the seat and pin move together around and beneath the underside of the latch, the pin 49 slides along the latch to the position shown in Fig. 9, and the inclination of the latch flattens toward horizon-

tal. Turning of the dog under the action of the abutment pin shifts the lugs 51B away from the stop 55 and over-balances the dog which continues to turn until stopped by engagement of the lug 51B and the stop 57 with the throat 51F facing along the underside of the latch toward the pin 49.

From bed position, of Fig. 8, and the latch position, Fig. 9, the seat 13 is raised to the position 13Y, of Fig. 5, the back remaining undisturbed on and supported by the frame. In this movement the pin 49 enters the dog notch through the facing throat 51F, is forced by the camming shoulder 45D of the latch toward the recess seat 51D of the dog, and turns the dog until the heavy side of the dog takes over and turns the dog against the pin. In Fig. 11, shift of the dog has occurred, but the pin and cam still control. Further shift of the pin under seat movement moves the pin outward solidly against the dog recess seat 51D and the latch shoulder 45A (Fig. 6) and stops seat movement in the position 13Y, with the pin at the entrance to the latch recess 45B, and dog shift prevented by engagement with the pin. Forward and downward return movement of the seat shifts the pin into the latch recess, both the weight of the latch and turning pull of the dog urging such engagement. Movement is continued until the seat comes to rest on the frame 19, and through the latch the back is shifted to sofa position. As this movement progresses, the spring 35 is brought under tension, easing the final seating movement, and as seating occurs, the pin 33 engages the shoulder 33A of the arm 23 and the end of the slot 39A of the stop arm engages the pin 41, establishing the originally described positionings and conditions of Fig. 1.

I claim:

1. In a sofa bed, including a seat and a back, having seat and back members respectively secured thereto, pivot means hinging said members together, and latch means coupling said members, a frame, and front and rear supporting arms, both pivotally connected at their lower ends to said frame, and respectively pivotally connected at their upper ends to said hinge pivot means and to said back member rearwardly of said pivot means, said rear arm having adjacent its upper end a shoulder, and said seat member including a part extending rearward of said hinge pivot into seating engagement with said shoulder, when said seat and back are in sofa position, to stop movement of said arms and brace said back.

2. In a sofa bed, including a seat and a back, having seat and back members respectively secured thereto, pivot means hinging said members together, and latch means coupling said members, a frame, and front and rear supporting arms, both pivotally connected at their lower ends to said frame, and respectively pivotally connected at their upper ends to said hinge pivot means and to said back member rearwardly of said pivot means, a pin carried by said rear arm adjacent its lower end, a stop arm pivotally connected at its front end to said front arm above said rear arm pin, and slotted intermediate its length to slidably engage said pin, the forward end of said slot seating against said pin when said back and seat are in sofa position to stop further movement of said support arm and effect bracing of said back, said stop arm extending beyond said rear support arm, and a tension spring of closed length less than said extension, secured to the

rear end of said stop arm and to said rear support arm to exert forward pull on said front supporting arm as said seat and back approach or leave sofa position.

3. In a sofa bed, including a seat and a back, having seat and back members respectively secured thereto, pivot means hinging said members together, and latch means coupling said members, a frame, and front and rear supporting arms, both pivotally connected at their lower ends to said frame, and respectively pivotally connected at their upper ends to said hinge pivot means and to said back member rearwardly of said pivot means, a pin carried by said rear arm adjacent its lower end, said rear arm having adjacent its upper end a shoulder, and said seat member including a part extending rearward of said hinge pivot into seating engagement with said shoulder, when said seat and back are in sofa position, a stop arm pivotally connected at its front end to said front arm above said rear arm pin, and slotted intermediate its length to slidably engage said pin, the forward end of said slot seating against said pin when said back and seat are in sofa position, to stop further movement of said support arm, said shoulder and cooperating hinge part, and said pin and slot engagement cooperating to brace said back in sofa position, said stop arm extending beyond said rear support arm, and a tension spring of less closed length than said extension secured to the rear end of said stop arm and to said rear support arm to exert forward pull on said stop and front supporting arm, as said seat and back approach or leave sofa position.

4. In a sofa bed, including a seat and a back, having seat and back members respectively secured thereto, pivot means hinging said members together, and latch means coupling said members, a frame, and front and rear supporting arms, both pivotally connected at their lower ends to said frame, and respectively pivotally connected at their upper ends to said hinge pivot means and to said back member rearwardly of said pivot means, and a stop arm pivotally connected at its front end to said front arm, and extending beyond said rear support arm, and a tension spring of less closed length than said extension secured to the rear end of said stop arm and to said rear support arm to exert forward pull on said front supporting arm when said seat and back are in sofa position.

5. In a sofa bed, including seat and back sections, pivot means hinging said sections together, and latch means coupling said sections, a frame, and front and rear supporting arms, both pivotally connected at their lower ends to said frame, and respectively pivotally connected to their upper ends to said hinge pivot means and to said back section rearwardly of said pivot means, and a stop arm pivotally connected at one end to a first of said support arms, and extending beyond the second said support arm, and a tension spring of less closed length than said extension secured to the extending end of said stop arm and to said second support arm to exert forward pull on said front supporting arm when said seat and back are in sofa position.

6. In a sofa bed, including seat and back sections, pivot means hinging said sections together, and latch means coupling said members; a frame, and front and rear supporting arms, both pivotally connected at their lower ends to said frame, and respectively pivotally connected at their upper ends to said hinge pivot means and to

said back member rearwardly of said pivot means, a stop arm pivotally connected at one end to a first said support arm, and extending beyond the second said support arm, said extending portion being longitudinally slotted, and a stop pin carried by said second arm disposed through said slot, said slot terminating in a closed end positioned to seat against said stop pin, as said back reaches sofa position.

7. In cooperation with a sofa bed hinge and an abutment pin carried thereby, a latch and a dog pivoted to said latch, said latch and dog being notched to form substantially equal length pin receiving recesses, and entrance openings leading thereto, said recesses being disposed with their inner ends equally spaced from said pivot, extending therefrom and diverging relatively the one to the other, said latch recess divergence being outward and downward, and said entrance being at the outer end of said recess, said dog entrance being at the inner end of its said recess, said dog having a camming edge extending away from said entrance and terminating in a pin engaging seat, said edge being spaced from said pivot in excess of the depth of said latch below said pivot, said dog being heavier on its recessed side and oppositely to said camming edge than oppositely thereto, and responsive to such weighting shifting in response to latch movements, means carried by said dog, and means carried by said latch cooperating to limit turning movement of said dog in one direction to position said dog entrance, and oppositely to position said dog camming edge in pin engaging relation below said latch.

8. In a sofa bed hinge, including hinge members, latching means including an abutment pin carried by one hinge member, and a latch swingingly attached at its inner end to the other said member and extending into overlying relation with said abutment pin, and being shiftable with relation thereto, said latch at its outer end being notched for pin engagement, a dog pivotally attached to said latch adjacent the outer end of said latch, said dog being indented outwardly from its attachment to form a pin receiving recess with said abutment pin, and being shiftable with said entrance being adjacent the inner end of said recess and being spaced to underlie said latch and faced to receive said abutment when said abutment is shifted outward along said latch,

said dog having a camming edge extending away from said entrance and terminating in a pin engaging seat, the lower edge of said latch having a downwardly bulging portion overriding said abutment pin to raise said latch and dog and align said dog recess entrance with said pin.

9. In a sofa bed, including back and seat members hinged together; an abutment carried by one of said members, a latch pivotally attached at its rear end to the other of said members and extending into overlying relation with said abutment, a cooperative dog and a pin pivotally attaching said dog to said latch, said latch forwardly from said pin being forwardly and downwardly recessed and upwardly notched into the forward end of said recess, to receive said abutment, said dog having a substantially semi-circular heavy half concentric with said pivot pin, a much lighter opposite half and a projecting lug, and being positioned by said pin in overlying relation to said latch notch; said heavy half being indented at one end to form a recess spaced equally with said latch recess from said pin, extending outward from said pin, and being notched at the inner end of said recess to receive said abutment, said lighter half being cut away at the same end to form a camming surface extending from said notch and spaced from said pivot to extend below said latch, said surface terminating in a trip lug, and means carried by said latch cooperating with said lug for respectively limiting turn of said dog in one direction to face said dog notch rearwardly below said latch, and in opposite direction, with said camming surface in underlying relation to said latch.
